UNITED STATES PATENT OFFICE.

FRANK F. AMBROSE, OF LOS ANGELES, CALIFORNIA.

SCREW PUMP.

Application filed April 19, 1926. Serial No. 102,869.

This invention relates to a screw pump of the type illustrated in Letters Patent No. 529,837, issued on November 27, 1894, to William E. Quimby, in which two pairs of intermeshing screws, right and left and left and right, respectively, are mounted in the same horizontal plane on parallel shafts journaled in bearings in the heads of a shell bored to fit the perimeters of the unintermeshed portions of the screws. The screws have threads of two or more convolutions and projecting hollow cores which, by holding the outer ends of the threads spaced apart from the heads of the casing and their inner ends spaced apart from each other, provide two end chambers and one centrally located chamber, and the necessary inlet and outlet openings to these chambers are formed through the lower and upper walls of the casing.

In the drawings forming a part of this application, Fig. 1 is a side elevation of my improved pump. Fig. 2 is an enlarged vertical cross section on the line 2—2 of Fig. 1.

Referring to the drawings 5 is the base block which is secured to any suitable foundation, such as the floor of the pump house not shown. 7—8 and 9 are pedestals which are mounted upon and secured to 5 in any suitable manner. Pedestals 7 and 8 are connected to the lower part or body 10 of the gear case which extends to the horizontal plane of the center of shafts 11 and 12. A top member or cover 13 adjustably mounted upon body 10 by bolts not shown together with split bushings 14 completes the gear case. Shafts 11 and 12 extend longitudinally through the gear case and are provided with herring-bone gears 15^a within the case, the gears being shown in dotted lines. Adjacent to the gear case is a pump chamber casing composed of a body member 15 and a cover member 16. Shafts 11 and 12 pass longitudinally through the pump chamber casing and have mounted thereon within said casing and in the pumping chamber intermeshing right and left and left and right hand screws like the screws described in said Patent No. 529,837, of which screws 17 and 18 are shown in Fig. 2. Member 15 is mounted upon base 5 and the dividing line between 15 and 16 is in the plane that passes through the horizontal central line of shafts 11 and 12 and the two members are adjustably connected. At the ends of members 15 and 16 are split bushings 19.

In the lower part of member 15 is the inlet chamber 20 which is provided at each end with two ports, one on each side, so that either side of the pump may be connected to the supply. A channel 21 connects chamber 20 with the pumping chamber 22 which last chamber is formed by the cover 16 and upper part of body 15. The screws in the pumping chamber have the ends reduced to form hubs, of which hubs 17^a and 18^a are shown in Fig. 2. The other screws on shafts 11 and 12 have like hubs which abut against hubs 17^a and 18^a thereby forming a central chamber 23 which chamber has outlet ports 23^a in body 15, either of which may be connected by a pipe 24 to a place of use. Cover 16 has central brace lugs 25 and 26 which are integral therewith or may be detachably connected thereto as desired. These lugs 25 are faced with wearing plates 27 and 28 the lower faces of which rest upon the hubs of the screws in the pumping chamber and thereby hold the threads of the screws from contacting with the cover when the pump is in operation. Shaft 11 projects from the gear case and is driven by any suitable power, illustrated in the drawings as motor 29. Shaft 12 projects from the pump chamber and is driven by a like motor 30.

By this construction if it is desired to pump oil or other liquid of a heavier viscosity than that for which the pump is designed the cover members of the pumping chamber can be shimmed up so as to provide a pumping chamber of a greater capacity, thereby enabling the pumping of a heavier liquid without waste of power. By providing inlet ports at both ends and in both sides of the inlet chamber casing, easier installation of the pump and greater pumping capacity is provided than if the inlet and outlet chambers had only one port in each and on one side only, but if desired the ports may be in one side only. By making the ports in the body member access may be had to all the parts without removing a power unit.

Having described my invention, I claim—

1. In a screw pump a pump chamber casing divided horizontally and longitudinally on the center line of the screws, said casing having formed in the upper portion a pumping chamber and in the lower portion an inlet chamber, said chambers having ports in the lower member of the casing, there being a suction port at each end and

a discharge port in the center of said lower casing member.

2. In a screw pump a pump chamber casing divided horizontally and longitudinally on the center line of the screws, said casing having formed in the upper portion a pumping chamber and in the lower portion an inlet chamber, said pumping chamber having an outlet in each side in the center and in the lower portion, said inlet chamber having ports on each side at the ends thereof.

3. A screw pump of the type described comprising a casing divided horizontally and longitudinally on the center line of the screws, said casing having ports in the lower portion, there being a suction port at each end and a discharge port in the center of said lower casing member; two parallel shafts journaled in bearings in the heads of said casing, two pairs of intermeshing right and left screws with threads rigidly mounted on said shafts, said screws having hubs at their meeting ends to form a short centrally located chamber open to the ends of the threads of the screws; and brace lugs secured to the cover of said pumping chamber having ports on each side at the ends thereof.

ber and engaging the hubs of the screws at their meeting points.

4. A screw pump of the type described comprising a casing divided horizontally and longitudinally on the central line of the screws; said casing having ports in both sides in the lower portion; and forming an inlet and a pumping chamber; two parallel shafts journaled in split bearings in the heads of said casing and passing through the pumping chamber; means to cause said shafts to rotate in unison; means to rotate said shafts, said rotating means being applied separately to each shaft; two pairs of intermeshing right and left screws with threads rigidly mounted on said shafts, said screws having hubs at their meeting ends to form a short centrally located chamber open to the ends of the threads of the screws; and brace lugs secured to the cover of said pumping chamber and engaging the hubs of the screws at their meeting points.

In witness that I claim the foregoing I have hereunto subscribed by name this 13th day of April, 1926.

FRANK F. AMBROSE.
